UNITED STATES PATENT OFFICE.

DON A. MICKLESON, OF RYAN, CALIFORNIA.

POCKET-KNIFE.

1,098,955.

Specification of Letters Patent.

Patented June 2, 1914.

Application filed December 21, 1912. Serial No. 737,935.

To all whom it may concern:

Be it known that I, DON A. MICKLESON, a citizen of the United States, residing at Ryan, in the county of Inyo and State of California, have invented certain new and useful Improvements in Pocket-Knives, of which the following is a specification.

My invention relates to improvements in pocket knives, and more particularly to an improved blade for use in such knives, said improved blade being particularly designed and adapted for use in crimping, corrugating, or fluting detonating caps in attaching the latter to fuses used in connection with the detonating of high explosives in blasting.

The improved blade may be found useful for similar or analogous purposes in other connections.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1, is a side elevation of a pocket knife provided with an improved blade in its open position. Fig. 2, a similar view of a modified form of blade detached. Fig. 3, an enlarged cross sectional view taken on line 3—3 of Fig. 1. Fig. 4, an enlarged longitudinal sectional view taken on line 4—4 of Fig. 2. Fig. 5, a view of a detonating cap and fuse showing the manner in which the cap may be fluted or longitudinally grooved with the improved blade or tool. Fig. 6, a similar view showing circumferentially extending grooves or corrugations formed in the cap by means of the improved blade or tool.

Similar numerals of reference designate like parts throughout all the figures of the drawings.

The improved knife blade 1, may be pivotally mounted and secured in any suitable and convenient form of knife handle or body 2, as illustrated in Fig. 1, of the drawings, and the knife blade 1, is provided with a toothed recess or irregular shaped notch 3, extending from one edge of the blade, and a similarly recessed movable member or plate 4, suitably mounted on and carried by the blade 1.

The toothed recess or opening 4^a, of the

movable member 4, is adapted to register with the toothed recess 3, of the blade 1, and to form a coöperating jaw for crimping, corrugating, or fluting the detonating cap 5, upon the fuse 6, and fastening or clamping the cap 5, upon the fuse 6, as illustrated in Figs. 5 and 6 of the drawings.

While I have shown a pair of teeth 3^a, and 4^b in the recesses 3 and 4^a, which are adapted to form the longitudinally extending grooves 5^a, in the detonating cap on opposite sides of the latter as indicated in Fig. 5, of the drawings, it will, of course, be obvious, that the number of such teeth and the form and arrangement of the same may be varied as desired.

As a convenient method of movably mounting and carrying the movable member 4, the latter may be slidably mounted transversely of the knife blade 1, at the base portion thereof by means of an inset slide or guide-way 1^a, intersecting or communicating with the recess or notch 3, as illustrated in Figs. 1 and 2 of the drawings, and in the form shown in Fig. 1, the transversely movable member is retained by means of overhanging guide lugs 1^b, while in the form shown in Fig. 2, the movable plate is provided with beveled sides fitted in correspondingly beveled or undercut sides 1^c, of the slide-way as shown most clearly in the enlarged longitudinal sectional view shown in Fig. 4, of the drawings.

The movable member 4, shown in Figs. 1, 2, 3, and 4, is preferably provided with a base stop in the form of a flange, as shown, said base stop being adapted to abut against the base portion of the blade when the movable member 4, is closed.

From the foregoing description, taken in connection with the accompanying drawings, the operation and advantages of my invention will be readily understood.

Having thus described some of the embodiments of my invention, what I claim and desire to secure by Letters Patent is,—

1. In a pocket knife, a pivoted blade provided with a toothed recess near its base and an intersecting transversely extending under-cut slide-way, and a slide plate mounted for transverse movement in the latter and provided with a similarly toothed opening and a stop in coöperative relation to said toothed recess and blade, respectively.

2. In a pocket knife, a pivoted blade provided with a toothed recess and an intersect-

ing slide-way, and a transversely movable member mounted in the latter and having a coöperating base stop and a similarly toothed recess adapted to register with said first-mentioned recess, the teeth in said recesses registering with each other.

3. In a pocket knife, a pivoted blade provided at its base with a toothed recess and an intersecting slide-way having under-cut sides, and a transversely movable member

mounted therein and having a toothed recess and a stop in coöperative relation to said first-mentioned recess and said blade, respectively.

In testimony whereof I have affixed my 15
signature in presence of two witnesses.

DON A. MICKLESON.

Witnesses:

C. D. ORENDRF,

THOMAS WILFRED GILL.
